UNITED STATES PATENT OFFICE.

EDWARD KENER, JR., OF BUFFALO, NEW YORK.

TOOL-HANDLE.

942,077.

Specification of Letters Patent.

Patented Dec. 7, 1909.

Application filed February 8, 1908. Serial No. 414,881.

To all whom it may concern:

Be it known that I, EDWARD KENER, Jr., a citizen of the United States, residing at Buffalo, in the county of Erie and State of New York, have invented a new and useful Improvement in Tool-Handles, of which the following is a specification.

This invention relates to an adjustable tool handle which may be readily attached 10 to or removed from different kinds and sizes of tools, such as files, chisels and soldering irons.

The object of this invention is to produce a handle of this character which is strong 15 and durable in construction, which can be quickly and securely applied to different tools and removed therefrom and which can be produced at comparatively low cost.

In the accompanying drawings consisting 20 of two sheets:—Figure 1 is a longitudinal section of one form of tool handle embodying my invention. Figs. 2 and 3 are cross sections in the correspondingly numbered lines in Fig. 1. Fig. 4 is a sectional perspective 25 view of the partially formed clamping sleeve or nut of my improved tool handle. Fig. 5 is a perspective view of the clamping sleeve in its completed form. Fig. 6 is a perspective view of one of the jaws of the 30 handle. Fig. 7 is a plan view of the partially formed body of the handle shown in Figs. 1, 2 and 3. Fig. 8 is a longitudinal 35 section showing another form of tool handle embodying my invention. Fig. 9 is a front elevation thereof showing the tang of a tool therein in section. Fig. 10 is a cross section in line 10—10, Fig. 8. Fig. 11 is a perspective view of one of the jaws employed in the tool handle shown in Fig. 8.

40 Similar letters of reference indicate corresponding parts throughout the several views.

The form of tool handle shown in Figs. 1—7 is designed to be made wholly of metal. 45 The body of this handle is constructed of a single sheet of metal so as to form two like arms or sections A, A which are connected at their rear ends by a transverse web *a* and each of which is semi-circular in cross section so that together they form a tubular or 50 hollow body. The rear parts of these body sections are provided with perforations *b* so as to permit the air to circulate freely through the same and keep the handle cool, 55 this being particularly desirable when the handle is applied to a tool which is heated

as for instance a soldering iron. The sections of the body are free to move toward and from each other radially for adapting them to different sized tangs of tools, this 60 movement of the body sections being permitted owing to the resilience of the web connecting the rear ends of the same. During this radial movement of the body sections the same are guided upon each other 65 but prevented from moving laterally with reference to each other by means of lips or ears *c* stamped out of the rear parts of the sections and bent inwardly from each body section and against the inner side of the adjacent portion of the other body section, as shown in Figs. 1 and 3.

The front end or shank of each body section has one half of a screw thread *d* formed thereon by stamping, the threads of both sections being so arranged that they lead from one to the other and together form a screw shank on this end of the body.

In making the body of the handle a flat blank is stamped between suitably constructed dies so as to produce the semi-circular formation of the sections and form the threads thereon while the sections are unfolded and arranged end to end, as shown in Fig. 7. The sections are then folded toward 80 each other along the central part of the connecting web *a* as a turning point and then the guide lips *c* are bent inwardly from each section and against the opposing section. Engaging with the exterior of the 85 threads of the screw shank is a screw threaded clamping sleeve or nut which together with the shank embraced thereby tapers forwardly so that upon screwing the sleeve rearwardly on the shank the front 90 ends of the body sections will be moved toward each other while upon screwing the sleeve forwardly the rear ends of the body sections are permitted to separate. This 95 clamping sleeve or nut may be variously 100 constructed but is preferably formed of a single piece of sheet metal which is first stamped from a blank so as to form two semi-circular threaded sections E, E arranged side by side, a longitudinal bead *e* 105 connecting the adjacent longitudinal edges of the sleeve sections and dished in the same direction as said sections, a longitudinal flange *f* arranged on the longitudinal edge of one of the sleeve sections and a channel *f* 110 arranged on the longitudinal edge of the other sleeve section, as shown in Fig. 4. The

sleeve sections are then bent toward each other on the connecting bead as a turning point and the channel on one section is interlocked or seamed over the flange on the other 5 section so as to securely embrace the same, thereby completing the circular form of the sleeve, as shown in Fig. 2. This bead and seam form shoulders, projections or abutments which permit a firm grip of the hand 10 to be obtained on the sleeve and thus enable the sleeve to be easily screwed on and off the handle body sections for tightening or loosening the same on the tang of the tool.

Within the front ends of the body sections or arms are arranged two gripping jaws which are adapted to engage with opposite sides of the tang of the tool to which the handle is applied. Each of these jaws is preferably constructed of metal and comprises 20 a semi-circular dished body G which tapers forwardly, a transverse web g arranged at the front narrow end of the jaw body and provided with a V-shaped notch or seat g^1 and a transverse rear web h arranged 25 at the rear or large end of the body and provided with a V-shaped notch or seat h^1 in line with that of the front web. Each of these jaws rests within the concave side of the front tapering portion of one of the 30 body arms and is secured therein both against radial and longitudinal displacement by means of retaining lips or lugs i formed on opposite edges of the respective body arm and bent inwardly against the concave side 35 of the jaw next to the inner sides of both of its transverse webs, as shown in Figs. 1 and 2.

For the purpose of applying the handle to a tool the clamping sleeve is screwed forwardly 40 on its arms to permit the front ends of the latter to separate the required extent. The tang of the tool is then inserted between the two jaws and engaged on each side with the V-shaped seats of the respective 45 jaw. Upon now screwing the sleeve backwardly upon the shanks of the body arms the same are drawn together and their jaws are firmly pressed against opposite sides of the tool tang so that the handle and tool are 50 firmly and reliably connected.

In the manufacture of this tool handle the use of solder is wholly eliminated, all the connections and fastenings being effected by bending lips or lugs so that the parts are 55 interlocked or connected and held in place.

In the modified construction of my improved tool handle shown in Figs. 8 to 11, the body of the handle is constructed of a cylindrical piece of wood which is split 60 lengthwise at its front end forming two arms A^1 , A^1 which are connected at their rear ends by the unsplit rear part a^1 of the body, while their front ends are constructed to form forwardly tapering shanks. The 65 opposing inner sides of these arms are pro-

vided at their front ends with grooves j, j the front parts of which are V-shaped for the reception of the tang of the tool to which the handle is to be applied. Upon the front end or shank of each of these arms is placed 70 a ferrule the inner part of which forms a jaw k provided with a V-shaped seat l while its outer part forms one half of an external screw m. The seats of both jaws are arranged opposite each other and are adapted 75 to engage with opposite edges or sides of the tang of the tool against which they are firmly held by means of a screw sleeve E¹ engaging with the threaded outer parts of the ferrules in the manner described with reference 80 to the construction shown in Figs. 1-7.

Each of the ferrules is preferably constructed of sheet metal and held in place on its body arm by means of spurs n arranged at the rear end thereof and driven inwardly 85 into the respective arm, as shown in Fig. 8.

My improved adjustable tool handle is not only convenient in use but also effects a considerable saving in expense inasmuch as it is more durable than the ordinary handle 90 heretofore in use.

I claim as my invention:

1. An adjustable tool handle comprising a hollow sheet metal body composed of two arms which are connected at their rear ends 95 while their front ends are each of semi-circular form and provided with external screw threads, a screw threaded sleeve engaging with the threads of said arms, and separate jaws arranged on the inner sides of the front 100 ends of said arms and adapted to engage a tool, substantially as set forth.

2. An adjustable tool handle comprising a hollow sheet metal body composed of two arms which are connected at their rear ends 105 while their front ends are tapered forwardly and provided with external screw threads and are each of semi-circular form, a forwardly tapering screw threaded sleeve engaging with the threads of said arms, and separate jaws arranged on the inner sides of the front 110 ends of said arms and provided with V-shaped seats which are adapted to receive the tool, substantially as set forth.

3. An adjustable tool handle comprising 115 an integral sheet metal body composed of two dished arms arranged with their concave sides facing each other and a transverse web connecting the rear ends of the arms, adjusting means connecting the front ends of said arms, and guide lips bent out of one of said arms and engaging with the other arm, substantially as set forth.

4. An adjustable tool handle comprising 125 an integral sheet metal body composed of two dished arms arranged with their concave sides facing each other and a transverse web connecting the rear ends of the arms, adjusting means connecting the front ends of said arms, and guide lips bent out of one 130

- of said arms and engaging with the inner side of the other arm, substantially as set forth.
5. An adjustable tool handle comprising a body having two arms connected at their rear ends and provided at their front ends with external screw threads and internal jaws, and a screw sleeve adapted to engage with the thread of the arms and comprising two sections constructed of sheet metal and secured to each other with their concave sides opposite each other, substantially as set forth.
10. An adjustable tool handle comprising a sheet metal body having two hollow arms connected at their rear ends, an adjusting device connecting the front ends of said arms, and jaws arranged on the inner sides of the front ends of the arms and each having a semi-circular body, and transverse webs arranged at the front and rear ends of the jaw body and lips formed on said arms and bent against said jaws for holding the same in place, substantially as set forth.
15. An adjustable tool handle comprising a body having two arms connected at their rear ends and having the exterior of their front ends provided with integral screw threads, and a screw sleeve engaging with the threads of said arms and constructed of sheet metal to form two semi-circular sections arranged with their concave sides facing each other and connected on one side by a bead while their opposite sides are connected by a flange arranged on the edge 20 of one section and a channel on the corresponding edge of the other section and embracing said flange, substantially as set forth.
25. An adjustable tool handle comprising a sheet metal body having two hollow arms connected at their rear ends, adjusting means connecting the front ends of said arms, and jaws arranged on the inner sides of the front ends of said arms and each constructed of hollow semi-circular form and held in place by a lip bent from the respective arm against said jaw, substantially as set forth.
30. An adjustable tool handle comprising a sheet metal body having two hollow arms connected at their rear ends, an adjusting device connecting the front ends of said arms, and jaws arranged on the inner sides of the front ends of the arms and each having a semi-circular body, and transverse webs arranged at the front and rear ends of the jaw body, substantially as set forth.
35. An adjustable tool handle comprising a sheet metal body having two hollow arms connected at their rear ends, an adjusting device connecting the front ends of said arms, and jaws arranged on the inner sides of the front ends of the arms and each having a semi-circular body, and transverse webs arranged at the front and rear ends of the jaw body, substantially as set forth.
40. An adjustable tool handle comprising a sheet metal body having two hollow arms connected at their rear ends, an adjusting device connecting the front ends of said arms, and jaws arranged on the inner sides of the front ends of the arms and each having a semi-circular body, and transverse webs arranged at the front and rear ends of the jaw body, substantially as set forth.
45. An adjustable tool handle comprising a sheet metal body having two hollow arms connected at their rear ends, an adjusting device connecting the front ends of said arms, and jaws arranged on the inner sides of the front ends of the arms and each having a semi-circular body, and transverse webs arranged at the front and rear ends of the jaw body, substantially as set forth.
50. An adjustable tool handle comprising a sheet metal body having two hollow arms connected at their rear ends, an adjusting device connecting the front ends of said arms, and jaws arranged on the inner sides of the front ends of the arms and each having a semi-circular body, and transverse webs arranged at the front and rear ends of the jaw body, substantially as set forth.
55. webs arranged at the front and rear ends of the jaw body and having V-shaped seats in their opposing edges, substantially as set forth.
10. An adjustable tool handle comprising a sheet metal body having two hollow arms connected at their rear ends, an adjusting device connecting the front ends of said arms, and jaws arranged on the inner sides of the front ends of the arms and each having a semi-circular body, and transverse webs arranged at the front and rear ends of the jaw body and lips formed on said arms and bent against said jaws for holding the same in place, substantially as set forth.
15. An adjustable tool handle comprising a sheet metal body having two hollow arms connected at their rear ends, an adjusting device connecting the front ends of said arms, and jaws arranged on the inner sides of the front ends of the arms and each having a semi-circular body, and transverse webs arranged at the front and rear ends of the jaw body and lips formed on said arms and bent against said jaws on the inner side of their bodies and adjacent to the inner side of their webs for holding the same in place, substantially as set forth.
20. An adjustable tool handle comprising a sheet metal body having two hollow arms connected at their rear ends and having their front ends tapering forwardly, adjusting means connecting the front ends of said arms, and jaws arranged on the inner side of the front ends of the arms and each consisting of a forwardly tapering hollow semi-circular body and transverse webs arranged at the front and rear ends of the body of each jaw, substantially as set forth.
25. A tool handle comprising a body constructed of sheet metal and having two arms which are connected at their rear ends and each of which is of concavo-convex form in cross-section, the concave sides of the arms facing each other and the front ends of said arms being provided on their outer sides with partial screw threads, and a screw nut engaging with the threads of both arms.
30. Witness my hand this 30th day of January, 1908.
